PAGE 2

Fig. 1 is a side perspective view of a wall telephone set showing our new design;

Fig. 2 is a perspective view, showing the set as seen from the left of Fig. 1; and

Fig. 3 is a front perspective view of the wall telephone set shown in Fig. 1.

Portions of the drawing figures are diagonally lined to indicate transparency, and the cord is partially broken away for convenience in illustration.

The dominant features of our new design are shown in solid lines in the drawing.

We claim:

The ornamental design for a wall telephone set, as shown and described.
